(57) **CLAIM**

We claim an ornamental design for a keyboard switch, as shown and described.

DESCRIPTION

FIG. 1 is a first perspective view of a keyboard switch showing our new design;

FIG. 2 is a second perspective view of the keyboard switch of FIG. 1;

FIG. 3 is a third perspective view of the keyboard switch of FIG. 1;

FIG. 4 is a front elevational view of the keyboard switch of FIG. 1;

FIG. 5 is a rear elevational view of the keyboard switch of FIG. 1;

FIG. 6 is a left side elevational view of the keyboard switch of FIG. 1;

FIG. 7 is a right side elevational view of the keyboard switch of FIG. 1;

FIG. 8 is a top plan view of the keyboard switch of FIG. 1; and,

FIG. 9 is a bottom plan view of the keyboard switch of FIG. 1.

The broken lines in the figures depict portions of the keyboard switch which form no part of the claimed design.
